UNITED STATES PATENT OFFICE.

MAX HERSKOVITZ, OF CHICAGO, ILLINOIS.

SWIVEL ARRANGEMENT FOR ELECTRIC TERMINAL PLUGS.

1,121,625.

Specification of Letters Patent. Patented Dec. 22, 1914.

Application filed July 12, 1913. Serial No. 778,663.

To all whom it may concern:

Be it known that I, MAX HERSKOVITZ, a citizen of the United States, residing in Chicago, in the county of Cook and State of Illinois, have invented a new and useful Improvement in Swivel Arrangements for Electrical Terminal Plugs, of which the following is a specification.

My invention relates to electrical terminal plugs and contemplates improved and simplified features of construction and arrangement which will decrease the manufacturing cost thereof and will at the same time increase the efficiency.

My invention relates particularly to swivel plugs and among its important objects are to provide construction involving a minimum number of simple parts; to provide construction which will enable the sleeve member to swivel readily; to provide improved contact mechanism which eliminate waste of electrical conductors and which will enable connections to be more readily made; to provide construction and arrangement which will hold the various parts together but which will at the same time allow free swiveling; and in general to provide improved, simplified and more efficient construction and arrangement in devices of the character referred to.

On the accompanying sheet of drawings, Figure 1 is a longitudinal diametrical sectional view of the plug, Fig. 2 is an end view thereof, Fig. 3 is a perspective view of the tip contact members, Fig. 4 is a perspective view of the plug parts separated, and Fig. 5 is a perspective view of the sleeve contact terminal.

The sleeve member S comprises a cup shaped head 10 of insulating material in whose end is permanently secured the base of the sleeve 11, this sleeve abutting against the internal shoulder 12. The outer end of the sleeve is threaded in the usual manner for engaging the threads of terminal sockets.

The tip member T comprises a core 13 of insulating material such as porcelain and has adjacent its end the peripheral groove 14 for receiving the contact ring or band 15, this band having at its outer edge the flange 16 against which the sleeve 11 abuts when the tip member is inserted therein. In the side of the tip member core is the pocket 17 for accommodating the terminal lug 18 extending from the band 15 and re-

ceiving the terminal screw 19, a passageway 20 extending from the pocket 17 to the base of the core for accommodating the conductor 21 leading to terminal screw 19. The tip member has the central longitudinal bore 22 for receiving the bolt 23 forming a conductor to the tip contact or washer 24 which is cup shaped to fit into the pocket 25 provided therefor in the end of the tip member. The lateral flange 24' on the contact 24 engages against the outer end of the tip member and contacts with the tip terminal of sockets into which the plug is screwed. The bolt 23 extends through the base of the cup shaped contact 24 and its head 23' engages in the contact and against the base thereof. The base of the tip member has the peripheral flange 26 extending therefrom within which flange is the tip terminal plate 27 engaging in the pocket 28 in the tip member base, the plate having the threaded opening 28' receiving the end of bolt 23, and carrying the terminal screw 29 for receiving the other conductor 30. Adjacent its base the tip member has the peripheral locking groove 31 for receiving the ends of spring tongues 32 formed in the sleeve 11 and forming integral parts thereof.

The sleeve member head 10 has the inlet opening 33 for the conductors 21 and 30. When the plug is to be connected with the conductors, the sleeve and tip members are separated, and the conductor ends slipped through opening 33 of the head 10, the conductor 30 is clamped by the screw 29 against terminal plate 27 while the conductor 21 is extended through passageway 20 to pocket 17 where it is clamped by screw 19 to the terminal lug 18. The tip member is now forced into the sleeve member until the locking groove 31 receives the ends of the spring tongues 32 and the end of sleeve 11 abuts against the flange 16 of the contact ring 15 on the tip member. The plug can now be applied to a terminal socket and the sleeve member rotated into threaded engagement with the socket sleeve, the tip member being carried into the socket without rotating and until its tip contact 24 securely abuts against the socket tip contact. During such rotation of the plug sleeve member the end of sleeve 11 works against flange 16 of the contact band 15, and after the plug has been fully inserted into the socket the end of the sleeve remains securely clamped against the flange 16 whereby the sleeve and band are

held in firm electrical engagement. The plug has thus efficient electrical contact with the socket and there can be no arcing.

It will be noted that the conductor screw 5 19 eliminates waste of conductors. In prior plugs one of the conductors extended entirely through the tip member to the tip contact and needed to be longer than the other conductor which extended only a short 10 distance to the other terminal. It was therefore necessary to cut a piece off of one of the conductors when connection was made with the plug, thus causing waste. In my plug such waste is not necessary as the terminal 15 screws 19 and 29 are both adjacent the base of the tip member. Such arrangement also enables the conductors to be more readily and easily secured to the terminals as it is unnecessary to pass one of the conductors 20 entirely through the tip member as in the prior construction referred to.

The plug comprises few and simple parts and can be cheaply manufactured, yet it is very efficient.

25 I do not, of course, desire to be limited to the exact construction and arrangement shown and described as changes may be possible which would still come within the scope of the invention.

30 I claim as follows:

1. In an electrical terminal plug, the combination with a sleeve member comprising a head and a threaded sleeve extending therefrom, of a tip member comprising a 35 core, a terminal bolt extending through the core and a terminal plate secured to the core base by said bolt, a contact ring on said core having a terminal lug extending therefrom,

and a flange on said contact ring, said sleeve fitting over said core and abutting against 40 said flange when the core is inserted in the sleeve.

2. In a swivel terminal plug the combination with a threaded sleeve, of a core having tip and sleeve contacts thereon, and a band 45 surrounding the outer end of said core and connected with said sleeve contact and having a flange forming an abutment for the sleeve when the plug is threaded into a socket.

3. In a swivel terminal the combination with a threaded sleeve, of a core having tip and sleeve terminals thereon and having an annular, peripheral groove, a contact band 55 held in said groove and connected to said sleeve contact, and a flange on said band forming an abutment for the sleeve when the plug is screwed into a socket.

4. In a swivel plug, the combination with a threaded sleeve of a core having a contact 60 tip and a contact band thereon, a terminal lug extending from said band toward the base of the core, a terminal plate on the base of the core, a bolt extending through the core and connecting said tip contact and terminal plate, and a flange on said band, said sleeve engaging against said flange when the core is inserted in the sleeve.

In testimony whereof I have signed my name to this specification in the presence of 70 two subscribing witnesses this 5th day of July, A. D. 1913, at Chicago, Illinois.

MAX HERSKOVITZ.
